ELECTRIC LAMP UNIT

Harry A. Douglas, Bronson, Mich., assignor to
 Kingston Products Corporation, a corporation
 of Indiana

Application March 17, 1934, Serial No. 716,207

12 Claims. (Cl. 240—41)

My invention relates to electric lamp units, and particularly to electric lamp units comprising an incandescent electric lamp mounted in a reflector, as in an automobile headlight, and the principal object of my invention is to provide a new and improved unit of this type. This application is a continuation in part of my application Serial Number 713,714, filed March 2, 1934. In the drawings accompanying this specification, and forming a part of this application, I have shown, for purposes of illustration, certain forms which my invention may assume, in these drawings:

Figure 1 is a longitudinal sectional view of one embodiment, showing the lamp in elevation.

Figure 2 is a fragmentary front view of the reflector.

Figure 3 is a front elevational view of the socket unit.

Figure 4 is a view showing the socket unit assembled with the reflector.

Figure 5 is a section through the lamp, on the line 5—5 of Figure 1.

Figure 6 is a view similar to Figure 4, but showing the lamp assembled with the socket and the reflector.

Figure 7 is a detail section, on the line 7—7 of Figure 6, while

Figure 8 is a view similar to Figure 1, showing another embodiment.

The embodiment of my invention disclosed in Figures 1 through 7 comprises a lamp 11 of the two-filament type, having a first filament 14 mounted between a common post 15 and a first selective post 16, and positioned in focus, for so-called bright light, and a second filament 17, mounted between the common post 15 and a second selective post 18, and positioned above the focal point, for so-called dim light. The three posts 15 and 16 and 18 are supported in the usual glass body 19, mounted in the lamp base 20, to which is secured the usual bulb 21, and the common post 15 is grounded to the exterior shell 22 of the lamp base 20, while the selective posts 16 and 18 are secured respectively to the contacts 23 and 24, carried by and projecting from the rear face of the lamp base 20.

Secured to the lamp base outer shell 22 is the tubular portion 25 of a positioning ring 26 which comprises also an outwardly extending flange 27 provided with three bayonet slots 28, spaced about the periphery of the lamp base 20, and provided also, on its rear face, intermediate the slots 28, with three positioning projections 29.

Receiving the lamp 11 is a reflector 12, com-

prising a body 30, which may be of parabolic form, and which is provided at its rear with an integral rearwardly extending tubular section 31 partially closed by an integral annular flange 32 extending radially inwardly from the rear edge of the tubular section 31. The flange 32 is provided centrally with an aperture 33 adapted to receive the lamp base 20, and at points spaced about the central aperture 33 is provided with three bayonet slots 34. Intermediate the slots 34 the flange 32 consists of surfaces 35 lying in a single plane perpendicular to the axis of the unit and adapted to be engaged by the positioning ring projections 29.

Receiving the rear of the lamp base 20 is a socket unit 13 comprising a cylindrical shell 36 provided at its forward end with an integral outwardly extending annular flange 37 provided with three apertures 38 through which extend the shanks 39 of three pins 40 provided at their forward ends with enlarged heads 41 and at their rear ends with swaged enlargements 42 by which the pins 40 are held against withdrawal from the flange 37.

Joining the three pins 40 is an annular disk 43 abutting the rear face of the reflector flange 32 and provided with three apertures 44 closely receiving the shanks 39 of the three socket pins 40, and provided on the disk 43 are three resilient loops 45 each provided near its free end with an aperture 46 receiving a cooperating projection 47 extending from the socket flange 37.

The shell 36 is provided at its rear end with three integral fingers 48 forming a seat in which is received an insulating base 49 substantially closing the rear end of the shell 36 and held between radially inwardly extending tips 50 on the fingers 48 and an inwardly extending flange 51 formed on the rear end of the shell 36 intermediate the fingers 48.

Slidably mounted in the insulating base 49 are two terminal rods 52, which are connected to conductors 53 leading to the control switch, as is well known in the art, and are provided at their forward ends with heads 54 adapted to contact the terminals 24 and 23 of the lamp base 20 and pressed into firm engagement with the lamp base terminals 24 and 23 by springs 55 encircling the terminal rods 52 and compressed between the insulating base 49 and the terminal heads 54.

Each of the positioning ring bayonet slots 28 comprises an entrance 56 adapted to receive a pin head 41, a seat 57 adapted to closely receive a pin shank 39, and a connecting portion 58 connect-

ing the entrance 56 to the seat 57. Each of the reflector flange bayonet slots 34 comprises an entrance 59 adapted to receive a pin head 41, and a seat 60 adapted to closely receive a pin shank 39.

Also provided in the pin connecting disk 43 are three lugs 61, adapted to be received in the entrances 59 of the reflector flange bayonet slots 34 when the pin shanks 39 are in the seats 60 of the slots 34.

The socket pins 40, and the pin positioning disk 43, may be positioned with the socket shell 36 by springing the resilient loops 45 to position the flange projections 47 within the loop apertures 46, and by then inserting the pins 40 through the apertures 44 of the disk 43, and through the apertures 38 of the flange 37, and then swedging the ends of the pins 40, to provide the enlarged rear ends 42 holding the pins in position and the parts assembled. The insulating base 49 may conveniently be assembled with the shell 36 by positioning it against the inwardly extending flange 51 before the inwardly extending ends 50 of the fingers 48 have been turned.

The entire socket unit 13 is assembled with the reflector 12 by inserting the pin heads 41 through the entrances 59 of the bayonet slots 34 in the flange 32 of the reflector 12, and rotating the socket unit 13 relative to the reflector 12, until the pin shanks 39 seat in the seats 60 of the bayonet slots 34, at which time the detent lugs 61 of disk 43 will snap into the entrances 59 of the slots 34, to releasably hold the socket unit 13 assembled with the reflector 12.

To assemble a lamp 11 in a reflector 12, the lamp 11 is inserted, with the entrances 56 of the bayonet slots 28 registering with the heads 41 of the pins 40, and then the lamp 11 is rotated, to bring the pin shanks 39 into the seats 57 of the bayonet slots 28, with the pin heads 41 overlying the adjacent walls of the lamp positioning flange 27, whereupon the spring loops 45, acting through the socket shell 36 and the pins 40, urge the projections 29 of the positioning ring flange 27 into tight engagement with the forward face of the reflector flange 32. Concurrently, the springs 55 hold the socket contacts 54 in firm engagement with the lamp base contacts 24 and 23.

To assure that any lamp 11 will be accurately positioned in any reflector 12, each reflector 12 is made accurately to gauge, entirely uniform for all practical purposes, and each lamp is placed in a standard, while its positioning ring 26 is still free, and accurately positioned, with the projections 29 of the positioning ring flange 27 in firm engagement with the part of the standard corresponding to the reflector flange 32, and the positioning ring 26 is then secured in fixed position on the lamp base 20, while the parts are so held, as by soldering 62.

To prevent partial insertion of a lamp 11, that is, engagement of the positioning ring flange 27 under part but not all of the pin heads 41, and the cocked positioning of the lamp 11 that would result therefrom, the pin heads 41 are preferably provided with extensions as shown, of a diameter greater than that of the seats 57 of the positioning ring flange bayonet slots 28 and projecting to an extent such that the flange 27 cannot be positioned beneath any of the pin heads 41 without the other pin heads 41 extending into the flange slots 28 to prevent seating rotation of the lamp 11 until the flange 27 is properly positioned below all of the pin heads 41.

By the use of three projections 29, spaced about the periphery of the lamp base 20, the lamp will be held firmly positioned, against any tilting, and by forming the bayonet connections unequally spaced, as herein shown, the construction will be such that the lamp can be inserted in only the one proper position. 5

From the foregoing it will be apparent to those skilled in the art that this embodiment of my invention provides a new and improved lamp assembly, accurately positioning the lamp, and readily and conveniently constructed, and accordingly, accomplishes at least the principal object of my invention. On the other hand, it also will be obvious to those skilled in the art that this particular embodiment of my invention may be variously changed and modified, without departing from the spirit of my invention, or sacrificing the advantages thereof.

For example, certain of the advantages are retained in the construction shown in Figure 8.

In this construction there is no reflector, and the socket unit is supported directly, as by a suitable support supporting the disk 43, and the lamp positioning ring 26 abuts directly against 25 and is registered directly from the disk 43.

Other modifications may be made, and in general, the disclosure herein is illustrative only, and my invention is not limited thereto.

I claim:

1. In combination: an incandescent electric lamp, having a base; a reflecting unit for said lamp; positioning means for said lamp, whereby said base and said reflecting unit are adapted to be brought into register at a plurality of points 35 disposed about the axis of said base; means, comprising a unit detachably mounted on said reflecting unit by relative rotation of said units, having parts engaging said positioning means, for pressing said positioning means into said 40 register with said reflecting unit; a plate, forming part of said detachable unit, based on said reflecting unit; and a projection on said plate, extending toward said reflecting unit, and cooperable with said reflecting unit to hold said 45 detachable unit in mounted position.

2. In combination: an incandescent electric lamp, having a base; a reflecting unit for said lamp; positioning means for said lamp, whereby said base and said reflecting unit are adapted to 50 be brought into register at a plurality of spaced points disposed about the axis of said base; means, comprising a unit detachably mounted on said reflecting unit, having parts engaging said positioning means, for pressing said positioning means and reflecting unit into said register; said 55 detachably mounted unit being mounted on said reflecting unit by bayonet connection means, seated by rotation relative to said reflecting unit substantially about the axis of said detachably mounted unit; a plate, forming part of said detachable unit, based on said reflecting unit; and a projection on said plate, extending toward said reflecting unit, and cooperable with said reflecting unit to hold said detachable unit in mounted 60 position.

3. In combination: an incandescent electric lamp, having a base; a reflecting unit for said lamp; said reflecting unit having circumferentially spaced bayonet slots having their entrance portions spaced circumferentially from their seat portions; positioning means for said lamp, extending laterally from said base, whereby said base and said reflecting unit are adapted to be brought into register at a plurality of spaced 70 75 portions.

points disposed about the axis of said base; said 5 positioning means containing a plurality of bayonet slots disposed about the axis of said base; means, comprising a unit detachably mounted on said reflecting unit, having parts engaging said positioning means, for pressing said positioning means and said reflecting unit into said register; said parts, and said slots in said positioning means, being constructed and arranged to make 10 bayonet connection with each other; and said detachably mounted unit being so constructed and arranged that said parts make bayonet connection with said slots in said reflecting unit and are seated by rotation relative to said reflecting unit 15 substantially about the axis of said detachably mounted unit.

4. In combination: an incandescent electric lamp, having a base; a reflecting unit for said lamp; said reflecting unit having circumferentially spaced bayonet slots having their entrance 20 portions spaced circumferentially from their seat portions; positioning means for said lamp, extending laterally from said base, whereby said base and said reflecting unit are adapted to be 25 brought into register at a plurality of spaced points disposed about the axis of said base; said positioning means containing a plurality of slots disposed about the axis of said base; means, comprising a unit detachably mounted on said reflecting unit, having parts engaging said positioning means and said reflecting unit into said register; said parts and said slots in said positioning means being constructed and arranged to make bayonet 30 connection with each other; said detachably mounted unit being so constructed and arranged that said parts make bayonet connection with said slots in said reflecting unit and are seated by rotation relative to said reflecting unit substantially 35 about the axis of said detachably mounted unit; and means for releasably holding said detachably mounted unit against detaching rotation.

5. The combination with a reflecting unit, of a 45 unitary device to which an incandescent electric lamp may be connected, said device comprising: a plurality of connector projections; a carrying member, carrying said projections; said projections being spaced from each other and extending 50 in the same general direction away from said carrying member; said projections having heads at their ends remotest from said carrying member; a washer member having apertures, smaller than said heads, through which said projections 55 are slidably disposed; and means, including a resilient part integral with said washer member, constructed and arranged to bias said washer member toward said heads of said projections and against said reflecting unit; and said reflecting unit having bayonet slots, cooperable with said heads, so constructed and arranged that said unitary device is detachably mounted on said reflecting unit by bayonet connection and seated by rotation relative to said reflecting unit substantially 60 about the axis of said unitary device.

6. In combination: an incandescent electric lamp having a base; a reflecting unit for said lamp; positioning means for said lamp, including a flange extending laterally from said base, whereby said base and said reflecting unit are 65 adapted to be brought into register at a plurality of points disposed about the axis of said base; said flange having circumferentially spaced bayonet slots having entrance portions and smaller seat portions connected by tapering intermediate

portions with said entrance portions; holding means, having projections provided with heads adapted to pass through said entrance portions of said slots and large enough to become seated on the margins of said seat portions, constructed 5 and arranged to hold said lamp connected to said reflecting unit and to press said positioning means into said register with said reflecting unit when said holding means and said positioning means are operatively assembled so that said 10 heads are seated on said seat portions; said positioning means and said heads being so constructed and arranged that they are so operatively assemblable by bringing said flange to underlie all of said heads and then rotating said 15 lamp about its axis; and said heads being of such diameter and axial length that when said flange is out of parallelism with the plane defined by said plurality of points and underlies one only of said heads, another of said heads will prevent 20 such rotation by engagement of the side surface thereof with the margin of an intermediate portion of one of said bayonet slots.

7. Securing means for holding an incandescent electric lamp to a mounting, comprising a unitary 25 article of manufacture connectible to and separable as a unit from the mounting, said unitary article including: a plurality of connector projections; a carrying member, carrying said projections; said projections being spaced from each 30 other and extending in the same general direction away from said carrying member; said projections having heads at their ends remotest from said carrying member; a washer member having apertures, smaller than said heads, through 35 which said projections are slidably disposed; and means, including a resilient part integral with said washer member, constructed and arranged to bias said washer member against said heads of 40 said projections.

8. A lamp assembly, comprising: an incandescent electric lamp, having a base; a reflector unit for said lamp; said lamp comprising positioning means adapted to be brought into register with said reflector unit at a plurality of places spaced 45 about the axis of said base; a pressing unit, detachably connected to said reflector unit, comprising parts engaging said positioning means, and so constructed and arranged that said parts act to press said positioning means into said register with said reflector unit; said pressing unit and said reflector unit comprising means constructed and arranged to connect said units, operable to connect or disconnect said units upon relative rotation of said units; and means for releasably holding said pressing unit in connected position, against disconnecting relative rotation, comprising a releasable holding member; one of said units comprising means mounting said holding member and against rotation relative to that 50 unit; the other of said units being provided with an aperture, and said holding member comprising a projection constructed and arranged to enter said aperture to hold said units against relative rotation; and said one unit mounting said 55 holding member for movement relative to both of said units, in the general direction of the axis of said pressing unit, between a holding position, in which said projection is disposed in said aperture, holding said units against relative rotation, 60 and a release position, in which said projection is withdrawn from said aperture, permitting such relative rotation.

9. In combination: mounting means, for supporting an incandescent electric lamp, having a 75

5 plurality of bayonet slots each having a generally circular entrance portion and a smaller seat portion spaced circumferentially from said entrance portions; and a lamp holding unit, including a member carrying a plurality of circumferentially arranged connector portions each having a shank and an enlarged head generally circular in cross-section; said heads being adapted to pass through said entrance portions and 10 become seated on said seat portions; said holding unit being so constructed and arranged that said connector portions are detachably connectible by bayonet connection with said bayonet slots, and that upon seating rotation of the bayonet 15 connection said shanks fit snugly but slidably in the circumferential ends of said seat portions; and said holding unit including means cooperating with said mounting means for releasably preventing unseating rotation of said 20 connector portions.

10. In combination: an incandescent electric lamp, having means providing a base for said lamp; mounting means, for said lamp, having a plurality of bayonet slots each having an entrance portion and a smaller seat portion spaced 25 circumferentially from said entrance portion; said base means including a lateral extension having a plurality of bayonet slots each having an entrance portion and a smaller seat portion 30 spaced circumferentially from said entrance portion; a holding unit, including a member carrying a plurality of circumferentially arranged connector portions each having a shank and an enlarged head; said heads being adapted to pass 35 through said entrance portions and become seated on said seat portions of said bayonet slots in said lateral extension; said holding unit being so constructed and arranged that said connector 40 portions are detachably connectible by bayonet connection with said bayonet slots in said mounting means, and that upon seating rotation of the bayonet connection said shanks fit snugly but 45 slidably in the circumferential ends of said seat portions of said bayonet slots in said mounting means; and said holding unit including means cooperating with said mounting means for releasably preventing unseating rotation of said connector portions.

11. A lamp assembly, comprising: an incan-

descent electric lamp, having a base; a reflector unit for said lamp; said lamp comprising positioning means constructed and arranged to register with said reflector unit at a plurality of places spaced about the axis of said base, to 5 position said lamp in said reflector unit; and securing means, constructed and arranged to secure said lamp in position; said securing means and said reflector unit comprising bayonet slot means detachably connecting said securing means 10 and said reflector unit, and comprising also latch means releasably holding said securing means and said reflector means against detaching relative rotation; and said securing means comprising spring means serving to resiliently hold said 15 lamp in position and to resiliently hold said latch means in latching position.

12. In combination: an incandescent electric lamp; mounting means for said lamp; said lamp having a base provided with a lateral extension 20 constructed and arranged to abut said mounting means; a holding unit, for said lamp, so constructed and arranged that said holding unit is detachably connectible to said mounting means; said holding unit including first and second members; said first member abutting said mounting means at the side thereof opposite from said lateral extension, and said second member being spaced from the first member; said first member being in the form of a plate having circumferentially spaced apertures; and connecting means, including connector members extending 25 between said spaced members and slidably through the apertures in said first member; said connecting means being so constructed and arranged that said second member is movable toward said first member, and that movement of said second member away from said first member is positively limited; and means, including 30 a resilient member integral with said plate at 35 one end and having its other end normally spaced from and engageable with said plate, constructed and arranged to bias said spaced members away from each other, and to positively limit the stress which may be put on said resilient member by movement of said second member 40 toward said first member.

HARRY A. DOUGLAS.
